(57) **CLAIM**

The ornamental design for a table, as shown and described.

DESCRIPTION

FIG. 1 is a top, front, left side perspective view of a table showing my new design;

FIG. 2 is a top plan view thereof;

FIG. 3 is a bottom plan view thereof;

FIG. 4 is a front elevational view thereof, the rear elevational view being a mirror image thereof; and,

FIG. 5 is a left side elevational view thereof, the right side elevational view being a mirror image thereof.

The horizontal lines near the bottom of the legs show a change of material from the wood grain above and is a lighter color from the upper part of the table.
